G. Smith, & H. Brown of Philadelphia Pa

Assignors to

Leibrandt and Mc Dowell (of same place)

Patent No. 1362 Dated Dec 13 1860

The schedule referred to in the Letters Patent of writing, for the same,

That it may concern:

Be it known that W. Garrison Smith and
Henry Brown, both of the City of Philadelphia and State of Pennsylvania,
have invented or produced a new and original Ornamental Design for a Stone
Base, and we do hereby declare that the following is a full and exact description
of the same, reference being had to the annexed drawings making a part of this
specification, in which,

Figure 1, represents the said base in perspective, and

Figure 2, a transverse section of the molding around the front edge
of the hearth, or base plate.

Like letters when on both figures, indicating the same objects.

The nature of our invention consists of certain carved ornamentations
on the plates which constitute the sides, top, and bottom of a stone base, as herein
after described, which base, for the purpose of nominal distinction, we will call
the "Elm".

In the drawings, A, is the right side plate, the left and back
plate, not seen in the figure, correspond in shape and ornamentation with
the said right side plate A. B, is the top plate, and C, the bottom plate.

The plate A, is ornamented on its central surface with the
raised figures, and, at its end boundary surfaces, with the raised figures 2, 2,
as seen in figure 1. The top plate B, has a molding (on each of its four edges)
ornamented with the surface convex projections or knobs 3, as seen in the figure, and
has also a raised figure 4, on each corner of its upper side. The bottom plate C, is
of the horizontal configuration shown in the figure 1, the front edge being finished
with a molding 11, whose transverse section is shown in figure 2. The surface
of the said molding is ornamented with the raised figures 5, 5, as seen in the

D4

figure. The right side edge of plate C, is finished with a moulding C, and raised ornamentation of a scroll in the figure; the left side and rear edges not seen in the figure are of the same form and have the same ornamentation as that of the right hand side C 97.

What we claim herein as our invention or production, and desire to secure by Letters Patent, is -

1st. The ornamentations 132, on the side and rear plates, as seen in plate A, as set forth and specified.

2nd. We claim the moulding on each of the four edges of plate B, the same being ornamented with the beads B, as seen in the figure, and also the figures C, on the upper side of plate B.

3rd. We claim the ornamented moulding H, on the front edge of the plate C, and also the ornamented moulding on the side and rear edges of the mid plate C, as shown at C 97.
